UNITED STATES PATENT OFFICE.

MARCELLUS M. HITT, OF LURAY, VIRGINIA, ASSIGNOR OF ONE-THIRD TO
JOHN A. BROADDUS, OF SAME PLACE.

AUTOMATIC CUT-OFF AND FILTER.

SPECIFICATION forming part of Letters Patent No. 643,355, dated February 13, 1900.

Application filed April 15, 1899. Serial No. 713,125. (No model.)

To all whom it may concern:

Be it known that I, MARCELLUS M. HITT, residing at Luray, in the county of Page and State of Virginia, have made certain new and useful Improvements in Automatic Cut-Offs and Filters, of which the following is a specification.

My invention is designed and adapted for use as an attachment of a rain spout or pipe which conducts water from a roof into a cistern or storage-tank. As is well known, when rain falls the water which first comes off a roof carries along with it more or less dirt, trash, and organic and mineral matter, and is thereby rendered unfit for drinking, if not for other uses in domestic service. My invention is adapted to turn aside this foul or dirty water, and thus prevent its entering the cistern, after which it operates automatically to deliver the cleaner water to the latter, besides filtering it on its passage thereto.

The features constituting the improvement are hereinafter described and claimed.

In the accompanying drawings, two sheets, Figure 1 is a central vertical section of the apparatus embodying my invention. Fig. 2 is a plan view of the same. Fig. 3 is a vertical section on the line 3 3 of Fig. 2. Fig. 4 is a perspective view illustrating the application of my invention as required for practical use. Fig. 5 is a side view of the apparatus, the cut-off and filter attachment being shown in the position required for conducting clean water to a cistern. Fig. 6 is an end view showing the parts in the same position as in Fig. 5.

A indicates the tank or receptacle for dirty water, B the automatic cut-off and filter constituting part of the spout or water-conductor leading to a cistern, and C the water-receptacle constituting a counterbalance for the pivoted cut-off.

D indicates the adjustable spout for gaging the delivery of water from the tank A to the counterbalance C.

The aforesaid tank A is preferably constructed of galvanized iron, and is open at the top, which is inclined, as shown, and also cut out on the sides to allow overflow in case of necessity. The combined cut-off and filter attachment B is arranged and supported in

the top of said tank A at an inclination of about thirty degrees. As shown in Fig. 4, the down-spout 1, connected with the eaves-trough, is attached to the conductor 2, (see Fig. 1,) which passes through the tank A to a cistern. (Not shown.) The automatic cut-off B is interposed in this conductor 2, and when in one position, Fig. 5, it forms practically a continuation of the same; but when tilted, as shown in Fig. 1, it operates as a cut-off proper and accordingly discharges water into the tank A. As shown in Fig. 1, the cut-off section 3 is pivoted at 4 to a supporting-hanger 5, which is permanently and rigidly attached to the enlarged sections 6 of the conductor 2. The cut-off section 3 is practically a short open trough having the same radius as the fixed sections 6 before referred to. One end of said cut-off section is weighted at 7, and its opposite end is provided with a filter 8. The latter is formed of sponge or other material permeable for water and arranged between two reticulated partitions 9. By this construction the filtering substance may be readily removed when required for the purpose of cleansing it. In its normal position the cut-off section 3 is tilted, as shown in Fig. 1, and consequently water delivered to it will be discharged into the tank A. On the other hand, when in practical alinement with the conductor 2, as shown in Fig. 5, it ceases to discharge water into tank A, and the same passes onward, through the filter 8, into the section of the delivery-pipe which extends to the cistern. The means for thus shifting or tilting the cut-off section 3 is the water-counterbalance C, before referred to. The same is a small, oblong, box-like water-receptacle, which is open at the top and pivotally connected with the lower end of the cut-off section 3 by means of a bent rod 10. It will now be perceived that when the first wash of a roof is delivered into the tank A, as indicated by arrows, Fig. 1, and fills the same up to the lateral discharge-spout B, it may flow through the slot or opening 11 (see Fig. 2) in said spout, and thereby be delivered into and fill the counterbalance C. The latter thus becomes weighted sufficiently to tilt the cut-off section 3 into the position shown in Fig. 5, and it will hold it in such position

so long as it remains filled with water, and consequently the clean water following the first wash, which has thus been delivered into tank A, will be filtered and conveyed to the 5 cistern. It is further obvious that this position and operation will be maintained so long as the rain continues.

In order to provide for discharge of water from the counterbalance C, and thereby permit 10 restoration of the cut-off section 3 to its original position, Fig. 1, I provide the same with an orifice 12, (see Fig. 3,) which permits the water therein to leak out in a comparatively short time. I also provide for a similar 15 discharge of the contents of tank A by setting the plug 13 of cock 14 (see Fig. 2) in such position as allows a slow escape of water. Thus in a short time after the fall of rain has ceased the entire apparatus will be 20 again in condition to operate as before and to avert from the cistern the first wash of the roof.

The lateral discharge-spout D, before referred to, consists of two parts—a fixed section 25 15 and a movable section 16, which is adapted to slide upon the former. The section 16 has a longitudinal slot 11, and it is obvious that by longitudinal adjustment of said section 16 more or less of said slot will be 30 exposed, as shown in Fig. 2. By this means the quantity of water which may pass through the slot 11 in a given time is easily regulated. It is further apparent that if the overflow from tank A is in excess of the quantity which 35 can pass through the slot 11 it will be discharged laterally upon the ground. As shown in Figs. 1 and 2, a small slot or opening 17 is formed in the bottom of cut-off section 3 for the purpose of allowing sufficient water to 40 discharge from said section into the tank A to supply the waste which necessarily goes on from the tank itself and from the counterbalance C during the time water is being discharged into the cistern. In other words, 45 the leak or discharge through said slot 17 prevents the counterbalance C becoming lightened sufficiently to allow the cut-off section 3 to tilt back prematurely to its normal position, Fig. 1.

50 My improved apparatus thus constitutes an efficient automatic cut-off for foul or dirty water and an equally efficient filter for the comparatively clean water following the first wash of the roof, and it automatically discharges and readjusts itself after every operation.

It will be seen that the cut-off section 3 being open at the top the removal of bugs and other organic or mineral matter, which may 60 collect adjacent to the inner filter-partition 9, may be effected without difficulty.

The entire cut-off and filter attachment B, together with the conductor-sections 2 form-

ing the ends thereof, may be quickly attached to or removed from the tank A. Each of the 65 said sections 2 rests in a cut-out portion of the tank and is secured in such position by means of a drop-pin 18 and a hinged bail 19. (See Figs. 1 and 6.) The said bail consists of a stout wire or small rod which is hinged 70 or pivoted to the tank on one side of the conductor-section 2 and is adapted to be hooked into the tank on the opposite side, passing intermediately over the conductor 2, as shown in Fig. 6. When the cut-off and filter attachment B is detached from the tank, it may be placed in the latter for the purpose of protection and economy of space in storage or transportation.

What I claim is—

1. In an automatic cut-off and filter apparatus, the combination, with the tank, having its top inclined and cut out at the upper and lower sides, of the cut-off and filter attachment, which fits and is held in such cut-out 85 portions, as shown and described.

2. The combination, with a tank, of a cut-off and filter attachment which is fitted in the top of said tank and supported thereby, and a hinge-bail and drop-pin for securing said 90 attachment removably, as shown and described.

3. The combination, with a water receptacle or tank, of a cut-off and filter attachment including as part of the same, a filter-compartment, arranged at one end of said section, and consisting of reticulated partitions and filtering material placed in the space between them, substantially as shown and described.

4. The combination, with the water tank or receptacle, and a pivoted cut-off arranged upon the same, of a lateral discharge-spout forming an attachment of said tank, and composed of a fixed section and a movable 105 section having a lengthwise slot which is exposed more or less according to the adjustment of the movable section, and a water-counterbalance arranged to receive the water discharged through said slot, substantially as 110 shown and described.

5. The combination, with a water-tank, or receptacle for the first wash of a roof, the same having a lateral discharge-pipe, of an automatic cut-off and filter attachment comprising alined, fixed, and inclined conductors 2, the intermediate, pivoted filter-section B, having a discharge-slot in the bottom thereof, a water-receptacle hung from the filter-section, and constituting a counterbalance 120 for the same, and having a discharge-slot in the bottom, as shown and described.
